Application March 1, 1928, Serial No. 258,180

9 Claims. (Cl. 66—36)

This invention relates to mechanism useful in connection with knitting machines in producing ornamental pattern effects in the fabric through occasional reversal of two contrastingly colored or physically differentiated yarns which are normally fed simultaneously to the needles of the machine in definite plating relation, so that the yarn normally relegated to the rear of the fabric is at times brought to the front for the purpose indicated.

Our invention is directed toward enabling the reversals of the plating yarns to be effected with absolute precision at each needle to the avoidance of overlap, as between neighboring wales, in the fabric produced by the machine; as well, as to enable such reversals to be selectively controlled at each needle in predetermining figurative pattern effects of any desired kind or scope.

The foregoing desiderata we secure with the aid of associate instrumentalities to individually displace knitting needles laterally with respect to others in the series just previous to drawing of the fabric loops with attendant reversal in their hooks, of the two yarns normally fed simultaneously in definite plating relation as aforesaid; and through provision of automatically operative means to select between the displacing instrumentalities in accordance with predetermined pattern designs.

As will appear from the detailed description which follows, the reverse plating mechanism of our invention lends itself readily to embodiment into the form of an attachment capable of application to standard types of knitting machines, more particularly circular hosiery knitters, without requiring extensive alterations or interfering with their normal cycle of functions in producing stockings or other knitted wares.

In the drawings Fig. I is a plan view of a typical seamless hosiery knitting machine equipped with the reverse plating mechanism of our invention.

Fig. II is an elevation of the machine viewed from the left of Fig. I.

Fig. IIa is a detail sectional view taken as indicated by the arrows IIa—IIa in Fig. I.

Fig. III is a fragmentary plan view of the knitting machine and the reverse plating mechanism on a larger scale than in the preceding illustrations.

Fig. IV is a view similar to Fig. III showing the parts of reverse plating mechanism in inactive position.

Figs. V and VI are fragmentary plan views on a still larger scale with portions broken away and in section.

Fig. VII is a longitudinal sectional view taken as indicated by the arrows VII—VII in Fig. III.

Figs. VIII and IX are transverse detail sections taken as indicated respectively by the arrows VIII—VIII and IX—IX in Fig. VII.

Fig. X shows in perspective a set of jacks by which the pattern of the reverse plated fabric produced by the machine is in part determined.

Fig. XI is a detail view taken as indicated by the arrows XI—XI in Fig. III.

Fig. XII is a perspective view showing one of the thrust cams embodied in the reverse plating mechanism.

Fig. XIII is a detail sectional view in accordance with the arrows XIII—XIII in Fig. I.

Fig. XIV is a detail section taken as indicated by the arrows XIV—XIV in Fig. III.

Fig. XV is a detail section viewed in the direction of the arrows XV—XV in Fig. XIV.

Fig. XVI is a plan view of a knitting needle, a sinker and associated push and pull instrumentalities whereby the needle is manipulated in determining reverse plating thereon.

Fig. XVII is a perspective view of the assemblage shown in Fig. XVI.

Figs. XVIII and XIX are perspective views respectively of the push and pull instrumentalities aforesaid.

Fig. XX is a diagrammatic illustration showing, in linear development, the relation of certain parts of the reverse plating mechanism to the knitting cams, the latch guard ring and the yarn feeds.

Fig. XXI depicts a typical fabric design such as may be produced with the reverse plating mechanism of our invention; and

Fig. XXII shows the manner in which the pattern jacks of Fig. X are arranged in the reverse plating mechanism to produce the patterned fabric of Fig. XXI.

As herein illustrated, the reverse plating mechanism of our invention embodies an annular head 25 which surrounds the sinker dial 26 and its cap ring 27 at the top of the needle cylinder 28 of the machine. The sinker dial 26 is made fast to the needle cylinder in the usual way so as to rotate and oscillate therewith in fashioning the heel and toe pockets of stockings. The cap ring 27 on the other hand is held stationary, except for capacity to circumferentially shift slightly as required during oscillatory knitting, through engagement of adjustable screw stops 29 (Figs. I and II) in upstanding lugs 30 with the arm 31 of the latch guard ring 32, said arm being pivoted at 33, for upward swinging, to a post 34 rising from the bed 50

40

45

50

55

55

plate 35 of the machine. From Figs. VII and XIV, it will be observed that the head 25 comprises two component parts or sections 36, 37 whereof the lower one 36 is circumferentially flanged inwardly as at 36a and secured to the sinker dial 26 by means of screws 38 extending through the flange. The upper head section 37 has a depending perimetric flange 37a which laps the periphery of the lower section 36 and is restrained against lifting by a number of removable angle clips 39 with horizontal legs reaching under said lower section, see Fig. XIV. The cap ring 27 for the sinker dial is in turn held from displacement vertically by clips 40 detachably secured to the upper head section 37, see Figs. III and XIV. After customary practice, the sinker dial 26 is radially grooved in its upper face to guide the sinkers S for reciprocation horizontally with respect to the needles N in the cylinder 28, the upturned butts of said sinkers running in the actuating cam groove 41 in the cap ring 27 in a manner well understood. Lying at one side of the sinker S in each groove of the sinker dial are push and pull instrumentalities 42, 43, see Figs. V, VI, XIV and XVII which operate upon the corresponding needle N as later on explained. As shown in Figs. V, VI, XVI and XVIII, the push instrumentality 42 is uniform in thickness throughout and disposed in a direct line with the needle N. Its horizontal shank 42a is of greater depth than that of the sinker; and the sinker groove of the dial 26 is counterrecessed as at 44 in Fig. XV to accommodate it. At the outer end, the push instrumentality 42 has a depending butt 42b; while its inner end is curved downward as at 42c to engage the shank of the needle N at a level somewhat below the top of the needle cylinder 28, see Figs. VII and XIV, and thus be out of reach of the latch of the needle when the latter descends to draw fabric loops. The horizontal shank 43a of the pull instrumentality 43 (Fig. XVII) is of the same vertical depth as that of the sinker S, and at the outer end has an upstanding butt 43b. Its inner end is curved downwardly as at 43c (like the instrumentality 42), and terminates in a hook 43d which engages the needle N within a circumferential recess 45 of the cylinder. To obviate necessity for excessively large cuts to accommodate the assemblage in each groove of the sinker dial 26, the pull instrumentality 43 is reduced in thickness through a portion of its length as at 43e (Fig. XIX) to provide room for the sinker S, the arrangement being clearly shown in Figs. XVI and XVII.

As shown in Figs. V, VI, VII and XIV the upstanding butts 43b of the pull instrumentalities 43 project into a raceway 46 provided for them in the upper part 37 of the head 25, said raceway being concentric with the axis of the needle cylinder 28. A portion of the inner wall of this raceway 46 is cut away as at 47 in Figs. V and VI and supplanted by complementary segmental cams 48, 49 which are respectively pivoted at their remote ends to swing about fulcrum screws 50, 51 while their contiguous ends inter-engage as at 52 over the stitch cam 53 (Fig. XX) which is active during rotary knitting; or in other words, in a line A—A slightly in advance of a line B—B through the stitch point in the illustration last referred to. With the segmental cam 49 are associated a pair of overlying supplemental segments 54, 55 capable of swinging independently of it and of each other on the screw 51. As shown in Figs. V, VI and XI, these supplemental cam segments 54, 55 are beveled at their free ends as at 54a, 55a, and over-

lap, to different extents, the juncture between the main cams 48, 49. Projecting vertically from the upper supplemental cam segment 54 through a slot 56 in the top of the head 25 is a stud 57 which is engaged by a leaf spring 58. Similarly, the supplemental cam segment 55 carries a stud 59 which projects up through a clearance aperture 60 in the superposed segment 54 as well as through a slot 61 in the top of the head 25 for engagement by a leaf spring 62. The springs 58, 62 act to normally maintain the supplemental cam segments 54, 55 in contact with a stop lug 63 on the segmental cam 49. With the several parts just described in the positions of Figs. III, V and VI, it will be apparent that as the needle cylinder 28 is rotated in the direction of the arrows, that the pull instrumentalities 43 will be drawn outwardly by the segmental cams 48—49 as they approach the yarn feeding station and stitch point of the needle actuating cams.

Referring still to Figs. III—VII it will be observed that the depending butts 42b of the push instrumentalities 42 are subject to engagement by pattern jacks 65 whereof there is a double series—one above the other—disposed in aligned radial upper and lower grooves 66 in the bottom part 36 of the head 25. These pattern jacks 65 have rearward projections 65a at different levels as shown in Fig. X, so that, by judicious selection and arrangement as exemplified in Fig. XXII, any desired pattern may be predetermined in the fabric knit by the machine as will be more fully explained hereinafter. To cooperate with the pattern jacks 65 we provide a system of thrust cams 67 (Fig. XII) in the form of elongated plates arranged at levels corresponding to the different projections 65a on said jacks and having centrally of their inner ends rounded cam protuberances 67a to engage such projections. As shown, the thrust cam plates 67 are divided into two groups at different elevations vertically (Figs. VII, XI) to correspond to the two sets of pattern jacks 65, and are slidably supported in an angularly disposed bracket 68 which is bolted to the side of the head 25 and centered on a radial line A, A' intersecting the line A—A in Fig. XX. The cam plates 67 are subject to leaf springs 69 engaging staggeringly-arranged studs 70 upstanding and depending from the components of the two cam plate groups, and having their ends anchored in opposite sides of the bracket 68. In order to permit of independent actuation, the cam plates 67 are variously cut out centrally as at 71 to clear the studs of their contiguous fellows in a manner which will be obvious from inspection of Figs. III and VII. Associated with each of the sliding cam plates 67 at the inner end are a pair of toggle pieces 72 (Figs. V, VI) which, as said cam plates are moved inwardly, act as gap closers, or in other words, assist in providing a continuous surface to contact with the butts 65a of the jacks 65 at opposite sides of the curved protuberances 67a. At the outer end, the bracket 68 affords bearing for horizontal longitudinally-shiftable plunger rods 78 which are suitably allocated in inclined parallel rows as shown in Fig. IX to cooperate at their inner ends with projections 67b on the contiguous ends of the cam plates 67. Beyond the region of the two groups of plunger rods 78, the bracket 68 has affixed to it by screws 76 (Fig. III, VII) a housing 77 accommodating corresponding sets of vertically-slidable auxiliary jacks 78, 79 which have edge notches 80 to cooperate with terminal cam 75

shoes 81 at the outer ends of said plunger rods. Individual springs 82 bearing on horizontal butts 78a projecting rearward from the upper set of auxiliary jacks 78, oppose operating levers 83 which engage said butts from beneath. As shown in Fig. I the operating levers 83 are fulcrumed at their outer ends to a fixed bar 84 suitably secured to the machine frame. A similar group of operating levers 85 is provided to effect actuation of the lower set of auxiliary jacks 79 through the medium of rockers 86 with pivotal support at 87 on the bracket housing 77 (Fig. VIII) and engaged by springs 88. The operating levers 85 are likewise afforded fulcrum support at their outer ends by another bar 89 also suitably made fast to the knitting machine frame.

To govern the operating levers 83, 85 just described we provide a control mechanism which is comprehensively designated at 90 in Figs. I, II and XIII, and shown as comprising a system of lifting levers 91 fulcrumed at their outer ends upon a common axis 92 which is jointly supported between a supplemental bracket 93 and an extension bracket 94 bolted to the machine frame. The levers 91 underlie the operating levers 83, 85, and at their outer ends are coupled with said operating levers through universal motion connections 95. It will be observed that the levers 83, 85 are graduated as to length, this being also true of the lifting levers 91 so that movement to the same extent is imparted through the thrust cam plates 61 and the pattern jacks 65, to the push instrumentalities 42 by the parts which are about to be described. Intermediate their ends the levers 91 are equipped with rollers 96 adapted to over-travel a corresponding series of pattern chains 97 trained upon a sprocket drum 98 affixed to a shaft 99 which is journalled in suitable bearings of the brackets 93, 94. Amongst the links of the sprocket chains are special cam links 97a capable of interchange and arrangement in accordance with the pattern desired in the fabric produced by the machine. When the reverse plating mechanism is in operation, the sprocket wheel shaft 99 is intermittently rotated as a consequence of the picking of a ratchet wheel 100 (Figs. I and IIa) thereon by a pawl 101 receiving vibratory motion by virtue of eccentric pivoting on a disk 102 at the end of a shaft 103 with bearing in the bracket 94. The shaft 103 is rotated through a pinion 104 in mesh with one of the gears 105 embodied in the driving mechanism of the machine (see Fig. II).

For greater diversification of pattern effects, we employ a master sprocket chain 106 to control pawling of the shaft 99 which carries the sprocket drum 98. This master chain 106 is trained about a sprocket wheel 107, which, together with an attached ratchet wheel 108, (Fig. II) is free upon the shaft 99. The ratchet wheel 108 is picked by a pawl 109 disposed alongside and pivoted on the same eccentric stud with the pawl 101 so as to be vibrated in unison with the latter. A spring detent 110 (Fig. II) prevents excess movement or overthrow of the ratchet wheel 108. The master chain 106 has special cam links 106a to under-travel a roller 111 on an arm 112 that is fulcrumed on the end of the axis 92 serving the lifting levers 91. A link 113 connects the arm 112 with one end of a centrally pivoted rock lever 114 whereof the opposite end rests on the top edge of a horizontal lever 115 with fulcrum bearing at 116 within the machine frame, see Fig. II. A vertically-reciprocable slide 117 (Figs. I and IIa) with bearing in a guideway 118 at

the side of the bracket 94 is coupled with the lever 115 by means of a link 119 and has a lateral projection 120 to under-reach the pawl 101. A coiled tension spring 121 tends to yieldingly urge the slide 117 upward with the rock lever 114 bearing on the lever 115. With this arrangement it will be apparent that lifting of the arm 112 through engagement of the roller 111 thereon by one of the cam links of the master sprocket chain 106 is attended by depression of the slide 117 and release of the pawl 101 to activity in stepping about the ratchet wheel 100 on the shaft 99 carrying the several pattern sprocket chains 97. The function of controlling the mechanism 90 is relegated to the timing mechanism of the machine, the intermittently rotating shaft 125 of the latter being to this end equipped with a supplemental cam drum 126, which, as shown in Figs. I and II, carries on its circumferential face, spaced rises 127-128 and 129-130 occupying different planes. The outermost set of cam rises 127-128 are effective upon a lever 131 which is rockable about a fixed stud 132 at the side of the machine frame in opposition to the pull of a tension spring 133. The movement of the lever 131 is communicated by means of a link 135 to a finger 136 pivoted at 137 to the bracket 94 and formed with a lateral projection 136a to under-reach both the pawls 101, 109. Thus when the lever 131 is engaged by the cam rises 127-128 of the supplemental drum 126, the pawls 101-109 are concurrently lifted away from the ratchet wheels 100-108 to suspend operation of the pattern mechanism 90. As a means to control the pawl 101 independently of the supplemental drum 126, we may provide the measuring chain 138 embodied in the timing mechanism of the machine with special high links such as shown at 139 to actuate the lever 115 for impartation of the necessary movement to the pawl-lifting slide 117.

During certain phases of the knitting, e. g., incidentally to fashioning of heel and toe pockets of a stocking when reverse plating is not desired or required, provisions are made as follows for moving to an inactive position, the segmental cams 48, 49 which affect the pull instrumentalities 43: Pivoted at 140 (Figs. I, III and IV) to the top of the head 25 is an arm 141 with an eccentric groove 142 in the lower face of its boss to engage the upstanding lug 63 of the segmental cam 49. Connected to the end of the arm 141 is an arcuate rod 143 capable of sliding movement in an aperture through a swivel stud 145 on the bracket 68. An arm 146 secured to a vertical axis 147 down through a boss 148 of the bracket 68 is coupled by means of a link 150 with the arcuate rod 143. A second arm 151 on the vertical axis 147 swingable beneath the bracket 68 is in turn coupled by a link rod 152 with a swivel stud 153 on one arm of a bell crank lever 155 (Figs. I and II) having fulcrum support at the side of the machine frame. Still another link rod 156 joins the other arm of the bell crank 155 with a rock lever 157 which is fulcrumed on the stud 132 inward of the rock lever 131 previously referred to. The free end of the rock lever 157 (Fig. II) lies within the path of the cam rises 129, 130 on the supplemental drum 126.

Assuming the reverse plating mechanism to be in action, the needle cylinder 28 rotating in the direction of the arrows in Figs. V and VI, and that two contrasting yarns Y, Y' are being concurrently fed at the proper relative tensions, from two feeds F, F' to the needles N in plating relation

as shown in Fig. XX, the operation of our invention is as follows: As previously stated, upon approach of the needles toward the yarn feeding and stitch forming regions, they are all flexed outwardly as shown in Figs. V and VI by action of the segmental cams 48, 49 upon the pull instrumentalities 43. Now if one of the levers 83, say that marked 83x in Fig. VII, is actuated by the pattern mechanism 90, the corresponding auxiliary jack 78x is lifted, (see Fig. VIII also), the aligned plunger rod 75x axially shifted inward, and movement imparted, as a consequence, to the associated thrust cam plate 67x to a like degree in opposition to its spring 69, to the end 10 that all the pattern jacks 65 with butts 65a in the plane of the cam plate 67x are engaged, one such jack being indicated at 65x in Fig. VII. Since the cam plate 67x lies in the line A—A' slightly in advance of the stitch point (Fig. XX), the 15 pattern jack 65x is alone projected inward through engagement by the rounded protuberance 61a of said cam plate. It therefore follows that the push instrumentality 42x subject to actuation by the jack 65x is in turn pushed inward, thereby displacing the corresponding needle Nx (previously moved out by the pull instrumentalities 43 with the others) inwards without effecting the immediately adjacent needles. The action just described takes place when the 20 butt of the push instrumentality 42x has just passed beyond the end of the segmental cam 48, and is made possible through capacity of the supplemental cam segments 54, 55 (associated with the segmental cam 49) to yield successively under 25 tension of the springs 58, 62. In other words, the butt of the selected push instrumentality 42x—immediately as it passes beyond the province of the segmental cam 49—is thrust inward, overcoming the spring 62 as in Fig. V and pressing 30 the cam segment 55 (the upper cam segment 54 being notched as at 54b for clearance of the butt of the push instrumentality 42x at this time) while the next succeeding push instrumentality is still riding on the segmental cam 49. Attention 35 is also directed to the fact that currently with the above events, the butt of the push instrumentality 42 immediately preceding the one marked 42x is being held out by the uppermost cam segment 54. As the movement of the 40 needle cylinder 28 continues, the butt of the selected push instrumentality 43x rides off the cam segment 55 whereupon the latter immediately slips back to its original place against the upstanding lug 63 of the segmental cam 49 to 45 intercept the immediately following push instrumentality 43 as shown in Fig. VI. At the same time, the selected push instrumentality 42x overcomes the tension of the spring 58 influencing the cam segment 54, this occurring just as the 50 needle Nx is about to draw the fabric loop at the stitch point and resulting in reversal of the yarns Y, Y' from the normal relation in the needle hook. With accomplishment of the yarn reversal in the hook of the needle Nx, the selected 55 push instrumentality 42x passes beyond the cam segment 54 whereupon the latter is at once returned by its spring 58 to its normal position against the upstanding stop lug 63 of the segmental cam 49 to check possible inward movement 60 of the push instrumentality 42 succeeding the selected one. Thus, in accordance with our invention, each needle upon which reverse plating is to be effected is thrust out of the plane generally followed by the other needles at that 65 time, with consequent reversal of the yarns in its 70

hook just before the fabric loop is drawn. The precise operation of the parts as described precludes the possibility of overlap of the reverse plated areas or regions into the field of normal plating in the body of the fabric with assurance of sharply defined figures in the pattern. The pattern knitted is predetermined through arrangement of the jacks 65 in the head 28, as well as by arrangement and diversification of the links as between the several sprocket chains 97 of the mechanism 98 which controls selection of the needles. The master sprocket chain 106 also plays an important part in the determination of the pattern through controlling the picking of the shaft 90 carrying the sprocket drum 98 for 15 the pattern chains 97—thereby causing repeat reversals on the same needles as required for example to produce the larger squares in the design shown in Fig. XXI. Incidentally to the knitting cycle of the machine, the measuring mechanism governs, through the interposed elements already described, activity of the pattern mechanism 98 and the segmental cams 48, 49 for 20 the pull instrumentalities 43 so that portions of the fabric—such as the heels and toes of a 25 stocking—may be knit plain as desired.

Although we have shown and described our invention as particularly useful in connection with hosiery knitters, it is of course to be understood that its scope is not so limited since its 30 adaptation to other types of knitting machines is clearly within the province of a skilled mechanician.

Having thus described our invention, we claim:

1. Reverse plating mechanism for knitting machines comprising push and pull instrumentalities for individual association with the knitting needles, and means to actuate the push and pull instrumentalities in effecting lateral displacement of corresponding needles relative to others with attendant reversal in their hooks, just previous to loop drawing, of two yarns normally fed simultaneously in definite plating relation. 35

2. Reverse plating mechanism for knitting machines comprising push and pull instrumentalities placed side by side in the guide grooves with the sinkers individually associated with the knitting needles, and means to actuate the push and pull instrumentalities in effecting lateral displacement of corresponding needles relative to others with attendant reversal in their hooks, just previous to loop drawing, of two yarns normally fed simultaneously in definite plating relation. 45

3. Reverse plating mechanism for knitting machines comprising push and pull instrumentalities for individual association with the knitting needles, means operative upon the pull instrumentalities to displace all the needles laterally outward from their normal positions as they approach the yarn feeding station, and means selectively operative upon the push instrumentalities to depress corresponding needles inward relative to others with attendant reversal in their hooks, just previous to loop drawing, of two yarns normally fed simultaneously in definite plating relation. 55

4. Reverse plating mechanism for knitting machines comprising push and pull instrumentalities for individual association with the knitting needles, a cam operative upon the pull instrumentalities to displace all the needles laterally outward from their normal positions as they approach the yarn feeding station, and selective means operative upon the push instrumentalities to depress corresponding needles inward relative 70

to others with attendant reversal in their hooks, just previous to loop formation, of two yarns normally fed simultaneously in definite plating relation, the cam aforesaid having sections capable 5 of yielding to permit the described action.

5. Reverse plating mechanism for circular knitting machines comprising needle displacing instrumentalities, individually associated with the sinkers in the slots of the sinker dial around the 10 needle cylinder, an annular head surrounding the sinker dial with radial slots accommodating interchangeable pattern jacks in line with the needle displacing instrumentalities said jacks having actuating butts in different planes, a set of thrust 15 cams lying in the planes of the pattern jack butts, and pattern mechanism to select between the thrust cams in causing, through coordinated pattern jacks and the respective displacing instrumentalities subject to them, lateral deflection of 20 corresponding needles relative to others in the series with attendant reversal in their hooks, just previous to loop drawing, of two yarns normally fed simultaneously in definite plating relation.

6. Reverse plating mechanism for knitting machines comprising push and pull instrumentalities individually associated with knitting needles, and means for actuating the push and pull instrumentalities to effect lateral displacement of their 25 associated needles relative to others with attendant reversal in needle hooks, just previous to loop drawing, of two yarns normally fed simultaneously in definite plating relationship. 30

7. Reverse plating mechanism for knitting machines comprising push and pull instrumentalities placed side by side in the guide grooves with the sinkers and individually associated with knitting needles, and means for actuating the push and pull instrumentalities to effect lateral displacement of their associated needles relative to others with attendant reversal in needle hooks, just previous to loop drawing, of two yarns normally fed simultaneously in definite plating relationship. 5 10

8. Reverse plating mechanism for circular knitting machines comprising a needle cylinder and independent needles slidable therein, means for sliding the needles for the formation of stitches, means for displacing the hook ends of all of the needles radially from normal position prior to the stitch forming point, and means for selectively effecting the return of certain needles to normal position thereafter but prior to the 15 stitch forming point.

9. Reverse plating mechanism for circular knitting machines comprising a needle cylinder and independent needles slidable therein, means for sliding the needles for the formation of stitches, means for displacing the hook ends of all of the needles radially outward from normal position prior to the stitch forming point, and means for selectively effecting the return of certain needles inward to normal position thereafter but prior to the stitch forming point. 20 25 30
